RESTRAINER TO MAINTAIN THE INOPERATIVE CONDITION OF A PULL-TYPE CIRCUIT BREAKER

Norman L. Hug, Cypress, Calif., assignor to McDonnell Douglas Corporation, Long Beach, Calif.

Filed Sept. 11, 1975, Ser. No. 612,377

Term of patent 14 years

Int. Cl. D8—08

U.S. Cl. D8—246

FIG. 2

FIG. 4

FIG. 5

FIG. 1 is a perspective view of a restrainer to maintain the inoperative condition of a pull-type circuit breaker embodying my new design;

FIG. 2 is a rear elevational view of the restrainer of FIG. 1;

FIG. 3 is a left side elevational view of the restrainer of FIG. 1;

FIG. 4 is a top view of the restrainer of FIG. 2; and

FIG. 5 is a bottom plan view of the restrainer of FIG. 2.

I claim:

The ornamental design for a restrainer to maintain the inoperative condition of a pull-type circuit breaker, substantially as shown.
